UNITED STATES PATENT OFFICE

SAMUEL SPANGLER, OF GLENALUM, WEST VIRGINIA

VALVE LOCK

Application filed March 19, 1929. Serial No. 348,287.

This invention relates to valve locks and has particular adaptation with a liquid supply pipe line.

One of the objects of the invention is to provide, in a manner as hereinafter set forth, for preventing unauthorized persons from withdrawing the liquid from the pipe line and is particularly applicable to preventing theft of automobiles wherein the lock is inserted in the gasoline line.

Further objects of the invention are to provide, in a manner as hereinafter set forth, a lock of the character described, which is strong, compact and durable, highly efficient for its intended purpose, thoroughly reliable in its operation, easily attachable to standard parts, very simple in its assembly and comparatively inexpensive to manufacture and install.

With the foregoing and other objects in view the invention consists of a novel construction, combination and arrangement of parts, as hereinafter will be more specifically described and illustrated in the accompanying drawings, wherein an embodiment of the invention is disclosed but it is to be understood that changes, variations and modifications may be resorted to without departing from the spirit of the claims hereunto appended.

In the drawings wherein like reference characters denote corresponding parts throughout the several views:

Figure 1 is a side elevation of the device in accordance with this invention,

Figure 2 is a vertical, central detailed sectional view,

Figure 3 is a horizontal, detailed sectional view taken substantially on line 3-3 of Figure 2, and looking in the direction of the arrows,

Figure 4 is a fragmentary diametric, detailed sectional view of the bushing and lock in accordance with this invention,

Figure 5 is a fragmentary horizontal section through the valve casing and valve stem showing the parts in locked position with the key removed, and

Figure 6 is a view similar to Figure 5,

showing the position of the parts in unlocked position.

Referring to the drawings in detail, wherein is disclosed an embodiment of the invention, 5 indicates a substantially cylindrical valve casing, the bottom of which merges into a longitudinally extending tubular portion 6 having a longitudinal passage 7 extending entirely through the tubular portion 6. It is pointed out that the outer surface of the tubular portion 6 may be formed of polygonal contour as will be understood by reference to Figure 1 of the drawings.

The opposite ends of the longitudinal passage 7 may be threaded as at 8, 9 to which are connected the opposed ends 10, 11 of a liquid supply pipe such as gasoline, water or the like.

The casing 5 and tubular portion 6 are formed with a circular opening 12 which extends entirely through both members in a transverse direction, the lower end of which communicates with a circular cavity 13 formed on the bottom of the tubular portion 6.

The cavity 13 is of greater diameter than the continuous opening 12. Rotatably mounted in the continuous circular cavity 12 is a valve stem 14, the lower end of which projects into the cavity 13, and the upper end of the said valve stem projects above the upper face of the casing and is formed with an annular turning cap 15 formed integral therewith.

A slot 16 extends diametrically through the valve stem 14 from the upper end thereof to a point near the passage 7 and is adapted for slidably receiving a key 17 and communicating with the slot 16 are a plurality of grooves of segmental configuration, axially spaced from each other. The grooves are indicated at 17 and extend inwardly from the outer periphery of the valve stem and extend thereabout for a quadrant so as to permit turning the valve stem 45 degrees about its axis when the key 17 is inserted in the slot 16.

A plurality of spring pressed plungers 18 are slidably mounted in cavities 19 formed in the walls of the casing 5 and communicate

with the diametric slot 16 and the segmental slots 17, depending upon whether the key 17' is inserted in the slot 16 as will be clearly understood by reference to Figure 2 of the drawings.

5 A cylindrical bushing lock 20 is adapted to be seated in the cavity 13 at the lower face of the tubular member 6 and is provided with a circular cavity 21 extending inwardly for a portion of its length. The lower end of the valve stem 14 is adapted to be confined within the socket 21 and adjacent the lower end of said valve stem it is formed with an annular groove 22 which registers with the inner end of an inverted T-shaped slot 23 which is formed in the walls of the bushing lock adjacent the cavity 21.

10 There are four of the inverted T-shaped slots 23 disposed about the walls of the bushing lock 20, ninety degrees apart as will be clearly understood by reference to Figure 3 of the drawing. Seated in the inverted T-shaped slots 23 are inverted V-shaped clamps 24 the apex of which normally projects above the inner face of the bushing slot 20. Intermediate the ends of the side walls of the cavity 13 there are formed four inwardly directed pockets 25 adapted to register with the inverted T-shaped slot 23 on the bushing lock 20 for the purposes to be presently set forth.

15 Near the lower end of the valve stem 14 it is formed with a circular opening 26 which extends diametrically therethrough. The opening is disposed on the valve stem so as to register with the passage 7 extending through the tubular portion 6 so as to form a continuous passage therethrough when the valve is open, while at the same time to present the solid walls of the valve stem across the opening to form abutments with respect thereto when the valve is closed.

20 In the application of the lock, in accordance with this invention, and in the assembly of the same, the valve stem is inserted through the central opening 12 and the bushing 20 is locked into position by forcing the apex of each member 24 into abutment with the inner wall of the cavity 13, the action of which forces the opposite legs 27, 28 into the groove 22 and the pocket 25 respectively whereby the valve and the bushing 20 are locked in position to prevent longitudinal movement thereof.

25 In locked position, with the key 17' removed as shown in Figure 5 of the drawings, the pins 18 extend through slots 17 into a portion of the diametric slot 16. When the key is inserted in slot 16, as shown in Figure 2 of the drawings, the edge of the key forces the inner ends of the pins 18 out of registration with the diametric slot 16, but these pins 18 are still projected into the segmental slots 17. In this latter position, as shown in Figure 2, the valve stem is free

30 to turn, and since these segmental slots 17 extend around a quadrant of the circumference of the valve stem, the said valve stem is permitted to turn 90° to bring the opening 26 into registration with the passage 7. The position of the pins 18 in the slots 17, when the valve is opened, is clearly shown in Figure 6 of the drawings.

35 Having thus described my invention, what I claim as new is:

1. In a valve lock of the character described, comprising a valve casing formed with a continuous passage therethrough, said casing being formed with a bore extending through the casing and across the passage, said casing also being formed with a recess communicating with one end of the bore, a cap bushing seated in said recess and having a socket therein registering with said one end of the bore, a valve stem having an opening for selective registration with said passage, said valve stem being rotatable in the bore and having one end rotatable in said socket, said valve stem being formed with a circumferential groove on that portion seated in said socket, expandable keys mounted in said cap bushing having one end of each engaging with said peripheral groove, and the other end of each engageable with the walls of the recess for locking the valve stem against longitudinal movement, the said valve stem being formed with a diametric key way through a portion of its length and also being formed with peripheral slots communicating with said key way, slideable pins mounted in the casing and projecting through said slots into said key way, and a key insertable in the key way for moving the pins in one direction.

40 2. In a valve lock of the character described, comprising a valve casing formed with a continuous passage therethrough, said casing being formed with a bore extending through the casing and across the passage, said casing also being formed with a recess communicating with one end of the bore, a cap bushing seated in said recess and having a socket therein registering with said one end of the bore, a valve stem having an opening for selective registration with said passage, said valve stem being rotatable in the bore and having one end rotatable in said socket, said valve stem being formed with a circumferential groove on that portion seated in said socket, expandable keys mounted in said cap bushing having one end of each engaging with said peripheral groove, and the other end of each engageable with the walls of the recess for locking the valve stem against longitudinal movement, the said valve stem being formed with a diametric key way through a portion of its length and also being formed with peripheral slots communicating with said
